UNIT HEATER FILTER FRAME

Fred M. Young, Racine, Wis., assignor to Young
Radiator Company, Racine, Wis., a corporation
of Wisconsin

Application November 19, 1952, Serial No. 321,434

5 Claims. (Cl. 183—74)

1

This invention relates to frame structures for mounting removable filters on standard unit heaters.

"Unit heater" is the common designation for a type of overhead space heater either suspended from the ceiling or set on a platform bracketed to a side wall. It comprises a series of exteriorly finned tubes, through which tubes a heated fluid flows, and wherewith is associated a fan for directing the heated air through the area between the fins for circulation out into the room to be heated.

When this type of heater is used in plants where the equipment involves the use of viscous materials, which in the course of their use inevitably contaminate the atmosphere of the room with atomized or vaporized particles thereof, the finned tubes of the heater in time become coated with concentrations of the viscous material. Obviously, these accretions tend to reduce the heat exchange efficiency of the heater. Under extreme conditions this reduced efficiency may be as great as fifty percent. Only the removal of this viscous coating will restore the heater to its expected efficiency.

Since these heaters are often suspended from a very high ceiling—or the wall platform is rather high above the floor—and the heating coil is connected to the heating fluid inlet and outlet conduits, it is an expensive operation to effect such cleaning. This is especially true if the heater has to be disconnected and lowered to the floor and the normal operation of the heating system interrupted. It, therefore, becomes advantageous to provide an efficient and economical arrangement for associating filters with a unit heater and which will extract these air-laden deleterious materials before the air reaches the heating coils.

The main objects of this invention, therefore, are to provide an improved frame structure for mounting air filters on conventional or standard unit heaters; to provide an improved filter frame structure of this kind which is simple in form, economical to manufacture, and easy to attach to the heating unit either before or after its installation; and to provide an improved filter frame structure of this kind which permits standard filters, of either the "throw-away" or "cleanable" type to be readily inserted and removed from operating positions on the unit frame structure.

In the accompanying drawings, illustrating this invention,

Fig. 1 is a rear perspective view of a standard unit heater equipped with a filter frame structure constructed in accordance with this invention, the filters being shown in place;

2

Fig. 2 is a similar view but showing the filters removed;

Fig. 3 is a horizontal sectional view taken on the plane of the line 3—3 of Fig. 1;

Fig. 4 is a vertical sectional view taken on the plane of the line 4—4 of Fig. 3; and

Fig. 5 is an exploded view of the several, specially-formed parts constituting a particular embodiment of this invention.

The essential concept of this invention involves the formation and assembly of a plurality of particularly-formed metal stampings for attachment to a unit heater housing so as to removably support a pair of standard filters in angular relationship to each other rearwardly of the heater fan, and through which filters the air is drawn before passing through the heating coil.

A unit heater, for use with which this filter frame structure is designed, comprises a housing 6 wherein is mounted a finned-tube heating coil 7 and back of which is arranged a motor-driven fan 8.

The embodiment of this concept shown in the accompanying drawings, comprises a pair of main mounting members 11 and 12, three spacing support elements 13, 14, and 15, and a pair of bracing plates 16 and 17, all of which are bonded together to form the frame structure with rectangular side openings 18 in front of which are supported the filters 19 the same being secured in position on the structure by a locking plate 21. As herein shown, all of these parts, constituting this improved structure, preferably are metal stampings all, except the locking plate, being spot welded together.

The main mounting members 11 and 12 are of irregular hexagonal shape three sides of which define a rectangular base section 22 and the other three sides define a trapeziform extension 23. The perimetrical portions along the short base section sides and the non-parallel sides of the trapeziform extension are bent over to provide transverse flanges 24. Opposed and parallel to each of these flanges along the extension 23 is an angle bar 25 bonded to the inner faces of the respective members 11 and 12 to form guideways 26 for the filters 19.

The spacing support elements 13 and 14 in cross section approximate a Z one leg 27 of which is considerably longer than the other and terminates in a flange 28. These elements 13 and 14 are bonded at their ends to the members 11 and 12 adjacent the base corners. The short leg 29 is disposed in alignment with the angle bars 25. The intermediate part 31 forms an abutment at the end of the guideway 26 for a filter 19.

The spacing support element 15 in cross section is somewhat channel shaped being formed by a web part 32 and divergent flanges 33. The web part 32 of this element 15 in width is somewhat less than the short side of the trapeziform extension 23. The element 15 is bonded at its ends to the respectively opposed inner faces of the members 11 and 12 slightly inward from the end of the extension 23 so as to dispose the flanges 33 in alinement with the angle bars 25, thus aiding in defining the guideways 26.

The bracing plates 16 are of right angle triangular form with integral flanges 30 formed along the right angle edges. These bracing plates 16 are set medially at the juncture of the spacing support element 15 and the members 11 and 12 and disposed rearwardly toward the respective base sections 22. The plates 16 are secured in this bracing position by having the flanges spot-welded to the element 15 and the members 11 and 12.

The filter locking plate 21 in cross section approximates the form of the element 15 except the web part 34 is slightly wider than the web part 32 of the element 15. A pair of bolts 35, extending through apertures in the web parts of the element 15 and the plate 21, with their winged nuts 36, hold the plate 21 with the flanges 37 against the filters 19 and serve to lock them in the guideways 26 to cover the openings 18. (See Fig. 3.)

The base sections 22 of the members 11 and 12 have apertures 38 formed therein along the rear edges whereby suitable fastening means—such as bolts and nuts—may be used to secure the structure to the housing 6 of the unit heater with the flanges 28 abutting the heater housing 6. The lower member 12 is provided with an insulating grommet 39 through which the electric wires lead to the unit heater motor.

With a filter frame structure of this kind, the standard unit heater, when used in plants where the air is contaminated with atomized or vaporized viscous materials, can be quickly and economically equipped with filters to protect the heating coils from acquiring an insulation of these viscous materials to the detriment of its proper functioning. Moreover, such a frame structure permits the filters to be readily removed for cleaning—or thrown away—and replaced without removing the unit heater or in any way disturbing the heating system.

I claim:

1. A filter frame structure for unit heaters comprising, a pair of spaced members each formed with edges converging rearwardly from the base thereof, supporting elements connecting together the members at their bases and converging ends to constitute rectangular open side spaces between the members, means for attaching the members along their respective bases to the opposite sides of a unit heater housing, and spaced flanges formed along the converging edges of the members to constitute guideways for the insertion and removal of standard filters to close the rectangular open spaces.

2. A filter frame structure for unit heaters comprising, a pair of members with trapeziform sections, transverse supporting elements bonded at their ends to the members adjacent the corners of their respective bases and adjacent the opposite parallel edges for disposing the members in spaced parallel relationship to constitute rectangular openings along the non-parallel sides of the members and along the bases thereof,

means for attaching the members along their respective bases to the opposite sides of a unit heater housing, and flanges arranged along the non-parallel edges of the members to constitute guideways for the insertion and removal of standard filters to close the rectangular side openings.

3. A filter frame structure for unit heaters comprising, a pair of members with trapeziform sections the non-parallel perimetrical portions of which are bent to form transverse flanges, transverse supporting elements bonded at their ends to the members adjacent the opposite parallel edges for disposing the members in spaced parallel relationship to constitute rectangular openings along the non-parallel sides of the members and along the bases thereof, the elements adjacent the base in cross section approximating a Z and disposed with one leg inwardly parallel to the respective member flanges, the other element in cross section being channel-shaped and secured adjacent the opposite parallel edges of the members, angle bars bonded to the opposed faces of the members in alinement with the one leg of the respective Z-shaped elements and with the flanges of the channel-shaped element so as to coat with the member flanges to form guideways for the insertion and removal of standard filters to close the rectangular side openings, and means for attaching the members along their bases to the opposite sides of a unit heater housing.

4. A filter frame structure for unit heaters comprising, a pair of members with trapeziform sections the non-parallel perimetrical portions of which are bent to form transverse flanges, transverse supporting elements bonded at their ends to the members adjacent the opposite parallel edges for disposing the members in spaced parallel relationship to constitute rectangular openings along the non-parallel sides of the members and along the bases thereof, the elements adjacent the base in cross section approximating a Z and disposed with one leg inwardly parallel to the respective member flanges, the other element in cross section being channel-shaped and secured adjacent the opposite parallel edges of the members, angle bars bonded to the opposed faces of the members in alinement with the one leg of the respective Z-shaped elements and with the flanges of the channel-shaped element so as to coat with the member flanges to form guideways for the insertion and removal of standard filters to close the rectangular side openings, a right angle triangular brace flanged along its right angle edges bonded medially to the inner faces of each of the members and the other element, and means for attaching the members along their bases to the opposite sides of a unit heater housing.

5. A filter frame structure for unit heaters comprising, a pair of members with trapeziform sections the non-parallel perimetrical portions of which are bent to form transverse flanges, transverse supporting elements bonded at their ends to the members adjacent the opposite parallel edges for disposing the members in spaced parallel relationship to constitute rectangular openings along the non-parallel sides of the members and along the bases thereof, the elements adjacent the base in cross section approximating a Z and disposed with one leg inwardly parallel to the respective member flanges, the other element in cross section being channel-shaped and secured adjacent the opposite parallel edges of

the members angle bars bonded to the opposed faces of the members in alignment with the one leg of the respective Z-shaped elements and with the flanges of the channel-shaped element so as to coact with the member flanges to form guideways for the insertion and removal of standard filters to close the rectangular side openings, a channel-shaped locking plate of cross section similar to the other element, means for removably attaching the locking plate to the other element to secure the filters in position in the guideways, and means for attaching the members

along their bases to the opposite sides of a unit heater housing.
